UNITED STATES PATENT OFFICE.

JAMES M. DALRYMPLE, OF TULSA, OKLAHOMA.

CHECKER-GAME BOARD.

Application filed January 8, 1927. Serial No. 159,866.

This invention relates to and has for one of its objects to provide a novel game board and novel game pieces with which may be played games that are surprisingly exciting and fascinating and to win which requires a high degree of alertness and keen powers of observation.

A further object of the invention is to provide a game board of the character stated on which the games hereinafter described are playable only and which shall permit two, three or four persons to play the games at one time.

The invention is hereinafter fully described and claimed, and illustrated in the accompanying drawing, wherein:

Figure 1 is a top plan view of the game board, and

Figure 2 is a plan view of one of each set of the game pieces.

The game board 1 is provided with a complete playing field of octagon contour and consisting of a centrally positioned sub-playing field and four home playing fields bordering the sub-playing field. The sub-playing field consists of forty-five alternately arranged red and white squares 2 and 3, respectively, and the home playing fields each consists of twenty-four alternately arranged black and white squares 4 and 5, respectively. The sub-playing field is partially square and has twenty of the red squares 2 over which the game pieces are moved during the playing of the games. The home playing fields which are spaced inwardly from the edges of the game board 1, are substantially oblong and each has fourteen of the black squares 4 on which the game pieces are played when arranging them preparatory to playing the games and over which they are moved during the playing of the games. The central and innermost of the black squares 4 of the home playing fields are located centrally within the margins of the sub-playing field, and arranged on opposite sides of each of such squares are two of the red squares 2. The respective home playing fields are separated by diagonal lines 6. The game board 1 is provided outwardly beyond the home playing fields with pips 7, 8, 9 and 10, and charts 11 and 12 which latter illustrate the manner in which the game pieces are to be placed in the home playing fields when arranging them preparatory to playing the games. There are four sets of the game

pieces, and each set consists of fourteen game pieces. One of them is known as the heart set, another as the diamond set, another as the club set and the other as the spade set. One game piece of each set is shown in Figure 2 and designated 13, 14, 15 and 16, respectively. The respective sets of game pieces are marked similar to the respective suits of playing cards. The pips, numerals and letters of the heart and diamond sets are red, and those of the spade and club sets are black, and the playing pieces are white, as illustrated in Figure 2. The respective game pieces of each set are known as the ace, king, queen, jack, joker, ten, nine, eight, seven, six, five, four, three and two or deuce.

A number of different games may be played with the game board and game pieces such for instance as "hi-lo-jack-game" and "the game of thirty-first". When playing either of these games each player uses a set of the pieces. When the first named of these games is to be played the game pieces are to be arranged on the home fields as shown in the charts 11, and when playing the second of these games the game pieces are to be arranged on the home fields as shown in the charts 12.

The general rules for playing these and other games are as follows: The last four black squares of each home playing field serve as a player's king row. No game piece can be moved backward from a red square except into an opponent's home playing field. After a game piece enters an opponent's home playing field it can be moved in any direction toward that opponent's king row. A king moves both forward and backward and is obtainable in any opponent's king row, or partner's. The lines 6 constitute barriers which prevent the game pieces from being moved directly from one home playing field to another home playing field. The joker can be omitted if desired, and when used always moves either forward or backward, in the same manner as the king. All available jumps must be taken, if seen in time by the player having the opportunity to jump, but one player cannot tell another of such chances even though it might work to his or her advantage to do so. A player failing to take an available jump should be blown a game piece by the player whose move next follows. Should that player fail to see the jump then the

chance to blow passes on to the player moving next in turn. No player can see-saw back and forth with the joker, unless there is no other safe move available. The joker should be used solely for the purpose of helping to eliminate an opponent's game pieces. A player cannot change a move after the fingers have been removed from the game piece. When two are playing, the players 10 use opposite home playing fields only. When three are playing, the center player treats as black squares the red squares, each located directly above the center forward square of each of the other two player's 15 home playing fields, and can move from them, only into black squares. The three players do not use any part of the fourth home playing field, and any three home fields may be used by them. When playing 20 partners, the partners use opposite home playing fields and should assist one another by blocking their opponent's moves etc. The players must take all available jumps whether they be partner's game pieces or 25 opponents', and partner's count score jointly. "Hi-lo-jack-game" is played as follows: The game pieces are arranged as shown in the charts 11. Ace counts high and deuce counts low. All game pieces are used in 30 counting game. The first player capturing an ace is credited with one point, the first player capturing a deuce is credited with one point, and the first player capturing a jack is credited with one point. When 35 counting game total the numerals on each players captured game pieces. As soon as the points high, low and jack are made game is counted and a new contest begun. The first player to obtain seven points wins the 40 game. Should the first ace, jack or deuce captured be used by a player for crowning an opponent's king the original capturer retains credit for the point. When a king is 45 jumped both game pieces count for the capturer (as game only) provided they do not have to be used for crowning an opponent's kings. If a player does not have a captured game piece with which to crown

an opponent's king he must then remove one of his own from the board to be used for the 50 purpose.

The game of thirty-first is played as follows: The game pieces are arranged as shown in the charts 12. Relative to kings, use same rules that govern the game of "hi-lo-jack-game". The first player to capture game pieces whose numerals total thirty or over 55 wins the game. All game pieces are used in counting score, ace counts four, king counts three, queen counts two, jack counts one, etc. 60

The game of elimination may also be played with the game board and game pieces. When playing this game there is no particular arrangement for a player's game pieces as their designation is not considered. Play 65 until all players but one have been eliminated, that one will be the winner. All general rules govern this game.

What is claimed is:—

1. A game board having a substantially 70 square sub-playing field consisting of forty-five alternately arranged areas of different colors, and substantially oblong home playing fields bordering the sub-playing field and each consisting of twenty-four alternately arranged areas of different colors, one area of each home playing field being arranged in the adjacent border of the sub-playing field and centrally between the ends of the border. 75

2. A game board having a substantially square sub-playing field consisting of forty-five alternately arranged areas of different colors, substantially oblong home playing fields bordering the sub-playing field and 80 consisting of twenty-four alternately arranged areas of different colors, one of the areas of each home playing field being arranged in the border of the sub-playing field and centrally between the ends of the border, 85 barrier indications between the adjacent ends of the home playing fields, and game pieces adapted to be arranged on alternate areas of two or more of the home playing fields. 90

In testimony whereof I affix my signature.
JAMES M. DALRYMPLE.
